Primary Examiner — Cary M Robinson

Assistant Examiner — Emily Anna Saunders

(57) CLAIM

The ornamental design for a dice game, as shown and described.

DESCRIPTION

FIG. 1 is a top perspective view of a dice game showing the new design;

FIG. 2 is a top perspective view of the dice game in an open configuration;

FIG. 3 is a bottom perspective view of the dice game in an open configuration;

FIG. 4 is a top plan view of the dice game;

FIG. 5 is a bottom plan view thereof;

FIG. 6 is a front elevational view thereof;

FIG. 7 is a back elevational view thereof;

FIG. 8 is a right-side elevational view thereof; and,

FIG. 9 is a left-side elevational view thereof.

The broken lines in the figures show portions of the dice game that form no part of the claimed design.

1 Claim, 9 Drawing Sheets
